ANTENNA

Harry H. Harsted, Chicago, Ill., assignor to Gephart Manufacturing Co., Chicago, Ill., a corporation of Illinois

Application January 25, 1943, Serial No. 473,492

7 Claims. (Cl. 287—20)

This invention relates, in general, to antenna of the type generally employed with aircraft, and which is usually attached to the wing in a position preferably to depend therefrom, and being of a rigid construction.

With antenna of this character it sometimes happens that in landing, as well as at other times, the antenna is struck by some object, and becomes broken or damaged to such an extent that, to repair the same, it is necessary to remove the entire mounting for the antenna. This is not only time-consuming and expensive, but is also, frequently, a very difficult task.

It is one of the objects of the present invention to provide in an antenna of this character, improved means for mounting the same whereby, when the antenna proper becomes broken or damaged, it may be readily removed or detached from its supporting base or anchor, and another one substituted therefor, while the base portion thereof remains attached or secured in position.

A further object is to provide an improved antenna of this character, which is preferably hollow and shaped to provide an air foil, whereby the speed of advancement of the aircraft to which it is attached, will not be impaired or interfered with.

A further object is to provide an improved mounting for antenna of this character, which may be readily attached to bases that are now in use, and which bases are already attached to the aircraft, without removing the base.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which

Fig. 1 is a view of a portion of the wing of an aircraft, having an antenna constructed in accordance with the principles of this invention attached thereto, and with a portion of the wing broken away.

Fig. 2 is a side elevation of the antenna, detached from the wing.

Fig. 3 is an end elevation of Fig. 2.

Fig. 4 is a detail sectional view, on an enlarged scale, taken on line 4—4, Fig. 3.

Fig. 5 is a detail sectional view taken on line 5—5, Fig. 4, with parts omitted.

Fig. 6 is a detail sectional view taken on line 6—6, Fig. 4.

Fig. 7 is an elevation of the connecting member which is disposed between the base and the adjacent end of the antenna element.

The antenna consists, essentially, of a base, here shown as comprising the members 10 and 11, constructed of any suitable material, prefer-

ably insulating material. In the form of the invention shown, these two elements are constructed separately, so that the section 11 may be readily applied to the section 10 when the antenna element is broken or removed, and which section 10 remains secured to the wing 12 of the aircraft. Obviously, the sections 10 and 11 may be formed integral, to be applied initially to the wing.

10 When these elements are formed separately, there may be provided a projection 13 on one of the elements, which enters a recess 14 in the other element, so as to maintain these elements against rotation one with respect to the other.

15 The element 11 is provided with a recess 15 which opens through the side of the element, and the bottom of the recess is provided with an opening 16 therethrough to receive a bolt or screw 17 that has threaded engagement with the element 10. This bolt 17 is preferably provided with a head 18 to form a shoulder 19 that rests upon the base of the recess 15, so that when the bolt is screwed into the element 10, the shoulder 19 will draw the element 11 tightly against the element 10 and secure the same together, the projection 13 entering the recess 14 co-operating therewith, to maintain the elements against relative rotation.

20 The numeral 20 designates a mast or antenna element proper, which is preferably hollow and is of an oval or elliptical configuration in cross-section, to provide an air foil, and this element 20 is comparatively thin with respect to its width. The element may be of any desired length, and 25 preferably tapers from its base to the tip thereof. The bottom of the element 20 is closed by a wall 21 which is provided with a screw-threaded opening 22.

25 The element 11 of the base is preferably tapered from the bottom thereof towards the top, and in the top surface thereof is provided a recess 23 on each side of the opening or recess 15. These recesses 23 have communication with the recess 15.

30 A connecting member 24 is provided with extensions 25, 26 extending from the top and bottom thereof, and these extensions are provided, respectively, with threads 27, 28 which run in opposite directions. The extension 26 is threaded into the base wall 21 of the antenna element 20, and the extension 25 is threaded into an opening 27a in the head 18 of the screw or bolt 17, the body of the connection 24 being of such an external diameter that it will fit within the recess or opening 15, and is of a diameter slightly greater than the thickness of the wall of the portion of the element 11 which is adjacent the opening 15.

35 In assembling or connecting the antenna element 20 with the base member 11, the extension 26 of the connecting member 24 is first threaded

40 into the opening 27a in the head 18 of the screw or bolt 17, the body of the connection 24 being of such an external diameter that it will fit within the recess or opening 15, and is of a diameter slightly greater than the thickness of the wall of the portion of the element 11 which is adjacent the opening 15.

into the opening 22 in the base wall 21 of the antenna element. The element is then positioned with respect to the base member 11, so that the extension 25 on the member 24 will enter the threaded opening 27 in the bolt or member 17, the member 24 entering the recess 15.

By then holding the element 20 in position with respect to the base, and rotating the member 24, the extension 25 will be threaded into the bolt 17, and, at the same time, the extension 26 will operate to draw upon the element 20 to cause its end 21 to enter and be seated in the recesses 23 in the base member 11. If desired, a fastening screw 18^a may be provided and threaded into the base member 11 to engage the periphery of the member 24. This member 24 may also be recessed, as at 29, so as to fit over the head 18 of the screw or bolt 17 when the parts are brought in close proximity.

In assembling the parts, it will be manifest that inasmuch as the recess 15 opens through the sides of the base member 11, access may be readily had to the connecting member 24 to rotate it, and to facilitate such rotation the periphery of the member 24 may, if desired, be knurled, or suitable openings 30 may be provided for a spanner wrench.

With this improved construction, it will be manifest that should the antenna element 20 become damaged or broken, it may be readily removed from the base by first withdrawing the screw 18^a and then rotating the connecting member 24, thereby rendering it possible to substitute a new element for the broken one. This antenna may also be attached to a base element 10 which is already secured to the aircraft wing, without removing the base, and, in that event, all that is necessary is to provide a recess 14 to receive the projection 13 on the member 11 to hold the latter against rotation, the two being secured together by the bolt or screw 17.

However, in the manufacture of this device, and where it is to be initially applied to the wing, these members 10 and 11, as before stated, may be formed as an integral structure. Being in the shape of an oval or ellipse in cross-section, the antenna will form an air foil, and the speed of travel of the aircraft will not be interfered with.

While in the present form of the invention the antenna is shown, in use, as being attached and dependent from the aircraft wing, it is to be understood that the same may be applied in any position desired, and while the preferred form and construction is herein shown and described, it is to be understood that various changes may be made in the details of construction, and in the combination and arrangement of the several parts, within the scope of the claims, without departing from the spirit of this invention.

What is claimed as new is:

1. Antenna embodying a base, means for anchoring the base, an antenna mast, means detachably securing said mast by one end to said base, and means associated with said base whereby said mast will be maintained against rotation with respect to the base, the first said means embodying mechanism disposed between the base and the adjacent end of the said mast and operable to draw said end towards the base.

2. Antenna embodying a base, means for anchoring the base, an antenna mast, means detachably securing the said mast by one end to said base, means embodying telescoping portions of said base and said mast for maintaining the

latter against rotation with respect to the base, the said means also embodying a rotatable member interposed between the base and the adjacent end of said mast, extensions projecting from opposite faces of said member and respectively engaging said mast and having connection with said base, and threads on said extensions running in opposite directions.

3. Antenna embodying a base, means for anchoring the base, an antenna mast, means detachably securing the said mast by one end to said base, means embodying telescoping portions of said base and said mast for maintaining the latter against rotation with respect to the base, the last said means also embodying a rotatable member interposed between the base and the adjacent end of said mast, extensions projecting from opposite faces of said member and respectively engaging said mast and having connection with said base, threads on said extensions running in opposite directions, and locking means for maintaining said member against rotation.

4. Antenna embodying a base, means for anchoring the base, an antenna mast, means detachably securing the said mast by one end to said base, means embodying telescoping portions of said base and said mast for maintaining the latter against rotation with respect to the base, said base comprising sections, means for securing said sections together, and interlocking means between the sections of the base for maintaining said sections against relative rotation.

5. Antenna embodying a base, an antenna mast, a connecting member provided with two sets of threads, said member being disposed between said base and the adjacent end of said mast and having threaded engagement with the mast and a connection with the base, one set of threads running in one direction and the other set of threads running in the opposite direction, said connecting member being housed within the base, said base having one or more openings whereby access may be had to said member to manipulate the same said base being of sectional construction, and means embodying interlocking portions between said base sections for securing them together against relative rotation.

6. An aircraft antenna embodying a base comprising two members, means for separably securing said members together and against relative rotation, an antenna mast one end of which abuts one of said base members, the abutting faces of said mast and said base member being provided, one with a recess irregular in cross-section and the other projecting into and conforming to said recess, whereby the mast and base member will be held against relative rotation, and means for securing the mast and the last said base member together.

7. An aircraft antenna embodying a base comprising two members, means for separably securing said members together, interlocking means between said base members for maintaining them against relative rotation, an antenna mast one end of which abuts one of said base members, the abutting faces of said mast and said base member being provided, one with a recess irregular in cross-section and the other with a portion projecting into and conforming to said recess, whereby the mast and the last said base member will be held against relative rotation, and means for securing the mast and the last said base member together.

HARRY H. HARSTED.
